SUSPENDED RAPID TRANSIT RAILWAY SYSTEM

Alphonso Davino, Los Angeles, Calif.

Application August 28, 1950, Serial No. 181,825

2 Claims. (Cl. 104—89)

This invention relates to rapid transit systems, and particularly to an overhead system which embodies an overhead track and cars suspended from the track and travelable therealong.

Suspension railway systems have been proposed in the past, such systems including a monorail and cars having wheels adapted to roll along the single track, at least one of the wheels being driven to propel the cars along the rail. Such suspension of the cars has the disadvantage of allowing the cars to sway sideways, particularly when maneuvering around a curve or when the cars are loaded unevenly. Such an unstable condition has been a serious drawback to the adoption of overhead suspension railway systems.

It is therefore an important object of this invention to provide an overhead railway in which the transportation cars are so suspended that side sway thereof is greatly minimized, and safer, more comfortable travel is assured. This object is best attained by providing a pair of parallel tracks and a car having pairs of transversely-spaced wheels which roll along the tracks. By this means, better balance of the car is effected and lateral rocking or swaying of the car is minimized.

Another object is to provide a system, of the character referred to, in which the spaced tracks have upstanding flanges which serve to retain the wheels on the tracks, the latter being preferably in the form of channels capable of taking side thrust of the wheels in either direction.

Another object is to provide a railway system of the type indicated in which each car has mounting frames at its top, the frames being U-shaped to provide spaced, vertical supports for the wheels, the mounting means also including resilient connections between the frames and the top of the cars. By this means, the cars are resiliently suspended and vertical shock loads are effectively absorbed to effect smooth operation.

Another object is to provide a system in which the wheels of the cars have pneumatic tires to further effect smooth, noiseless travel of the cars along the dual tracks. A related object is to provide roller means associated with each wheel and adapted to roll along the tracks and support the car in the event that the tire of the wheel becomes deflated, this being a safety feature.

Another object is to provide an overhead railway system which includes spaced, vertical columns or towers, each tower having at least one lateral cross-arm at its upper end and a supporting element depending from the outer end of the cross-arm, the element serving to support the pair of rails or tracks. A related object is to provide a catenary type suspension means for supporting the rails at points intermediate the towers. In accordance with the invention, the longitudinal members of the suspension means may be in the form of adjustable rods to which the vertical members of the suspension means are connected.

Another object is to provide an overhead suspension type railway system in which the car or cars have electric driving means, the electricity for operating the same being

2

supplied through a trolley wire extending lengthwise of and carried by the track, the invention further providing an improved trolley roller means resiliently mounted on the car and normally urged upwardly to cause the roller to engage and roll along the trolley wire. The resilient mounting is so constructed that the trolley roller can move vertically and also laterally in either direction, as the car is propelled around curves.

Another object is to provide a Y-type switch which is operative to guide the car from a main line onto a branch line, the movable switch member including a pair of the tracks or rails and being shiftable, by pivotal action, to a first position in which it aligns with and forms part of the main track, and to a second position in which its ends are disposed in alignment with one end of the main track and an end of the branch track.

A further object is to provide such a switch which is operated by a reversible electric motor carrying a pinion gear in mesh with a curved gear rack mounted on the shiftable switch member and arranged concentric with the pivot thereof. A related object is to provide switch means arranged alongside the tracks and remote from the switch by which the car can energize the switch motor to shift the switch member in the appropriate direction.

A further object of the invention is to provide vertically movable gates adapted to be alternately raised and lowered above the main track and the branch track, said gates being disposed beyond the shiftable switch member at the end remote from the pivot. Another object in this respect is to provide cable means operative to simultaneously raise one gate and lower the other gate, the cable means being adapted to be wound onto and unwound from a drum rotated by the switch motor. By this means one cable is wound as the other cable is unwound to effect lowering of either gate and raising of the other gate. Since the rotation of the drum is synchronized with the switch operating mechanism, the gate in the path of contemplated travel of the car is raised while the other gate is lowered to provide a barrier or stop for preventing a car from running off the end of the open track.

A still further object is to provide a system of warning lights for indicating to the operator of a car whether the switch and the gate, which is disposed above the track on which the car is traveling, are properly set to allow the car to pass through the switch in the selected direction. In accordance with the invention, the signal lights are connected in electric circuits which include switches, the latter having actuator arms operatively connected to the gates so as to be operated by movement thereof to upper and lower positions.

Further objects will appear from the following description and from the drawing, which is intended for the purpose of illustration only, and in which:

Fig. 1 is a side view of a portion of the overhead rapid transit system of my invention;

Fig. 2 is a cross-sectional view, taken on line 2—2 of Fig. 1;

Fig. 3 is an enlarged plan view of a portion of the track, showing a Y type switch and actuating means therefor;

Fig. 4 is a longitudinal sectional view, taken on line 4—4 of Fig. 3;

Fig. 5 is a cross-sectional view, taken on line 5—5 of Fig. 3;

Fig. 6 is an enlarged end view of the transportation car, showing the driving means for propelling the same along the track;

Fig. 7 is an enlarged view of the trolley connection of the car;

Fig. 8 is a detail of one of the tie members of the truss structure;

Fig. 9 is a side view of a safety device employed on the car; and,

Fig. 10 is a fragmentary cross-sectional view of an alternative form of overhead rail suspension means.

Referring to the drawings in detail, my improved railway system is of an overhead type, that is, a system in which a transportation car 10 is suspended from and travelable along a track 11. As an important feature of the invention, the track 11 is composed of a pair of transversely spaced rails 12 of channel shape, each rail having a horizontal track portion 13 and upstanding flanges 14 at its lateral edges. As shown in the drawings, the rails 12 are connected at longitudinally spaced intervals by cross-struts or connecting beams 15. The track 11 is suspended between spaced towers 20 of structural steel, the towers having lateral arms 21 between which extend suspension cables 22 which support the track by means of vertical elements 23. In lieu of the cables 22, the catenary suspension may utilize rods 25 (Fig. 8) which are joined in end-to-end relation by turnbuckles 26. At the towers 20 the track is carried by a supporting structure 27 extending downwardly from the arms 21. While a single track 11 may be supported by and between the towers 20 if desired, Fig. 2 illustrates a pair of tracks 11 extending parallel to each other, this arrangement permitting travel of cars in the same or opposite directions. Since the railways at each side of the towers are identical, only one is described in detail.

Each car 10 is preferably of streamline contour as shown in Fig. 1, and has doors 29 by which passengers may enter and leave the car, the railway system also including platforms or stations located at and carried by certain of the towers 20, these platforms not being illustrated. The car 10 is suspended from and mounted to travel along the track all by means to be next described. The car 10 has a pair of longitudinally spaced, upwardly projecting posts or pivots 33 which are pivotally connected to substantially U-shaped support members 34, these members having upstanding portions 35. Each portion or arm 35 carries an axle on which a traction wheel 36 is rotatable, each wheel having a pneumatic tire. The axles extend normal to the longitudinal axis of the car so that the wheels are adapted to roll along the rails 12 of the track 11. It is important to note that the wheels are retained in the channel-shaped rails by the flanges 14. By the double rail arrangement, side sway of the car is minimized. Due to the pivotal connections 33, the supporting members 34 can pivot with respect to the car to adapt the latter to negotiate curves, switches, etc. The upper ends of the pivots 33 have flanges or heads 37 and disposed between these heads and the lower connecting bars of the support members are compression springs 38 which serve to absorb shocks and vibration. By the use of the springs 38 and the pneumatic tires on the traction wheels, smooth, quiet travel of the car along the track is assured.

As shown in detail in Fig. 6, at least one of the support members 34 has upper laterally and inwardly extending portions 39 which support the wheel axles 40 by means of brackets 41. Each axle 40 carries a bevel gear 41' which meshes with a similar gear 42 on a vertical shaft 43. Also keyed to each shaft 43 is a bevel gear 44 which meshes with and is driven by a smaller bevel gear 45 fast on the armature shaft of an electric motor 46. Each driving motor 46 derives its electrical energy from a trolley wire 47 carried by and suitably insulated from bars 48 supported at spaced intervals along the railway. As shown in Fig. 6, trolley shoes 50 resiliently carried by the support member 34 may be utilized for contacting the trolley wires 47. In another embodiment (Fig. 7), the support member 34 may carry posts or rods 52 on which a plate 53 is slidable vertically, a spring 54 normally urging the plate upwardly. Bearing elements 55 projecting upwardly from the plate 53 support the ends of a transverse shaft 56 on which

5 a grooved trolley roller 57 is rotatable. Springs 58 tend to centralize the roller 57 and adapt the roller to shift laterally. By this means, the trolley roller 57 is maintained yieldingly engaged against the trolley wire 47. As 10 is common in conventional electrically-driven transportation cars, a suitable control switch or rheostat is provided in the car by which the operator can energize the motors 46 and regulate their speed so as to attain selected speeds of travel of the car along the track, and suitable 15 brake means (not shown) should, of course, be provided for bringing the car promptly to a stop.

Referring to Fig. 9, my invention contemplates the provision of safety means for retaining the car suspended by the track 11 in the event that a pneumatic tire of a 20 wheel 36 becomes deflated. This means consists simply in an auxiliary roller or small wheel 60 mounted in rear of a wheel 36 and normally elevated slightly above the track 11. Should a tire of a wheel 36 become deflated and the car tend to lower at this point, the auxiliary wheel 60 will engage and roll along the track. As an added 25 precaution, the car 10 may have upwardly projecting hooks 62, the upper ends of which overlie the laterally and outwardly projecting ends 63 of bar cross member 64 supported below U-shaped yoke support member 34 by means of struts 65. Upstanding lugs 66 project upwardly from the ends 63 of the bar cross member preventing lateral disengagement of the upper ends of the hooks 62 as shown in Fig. 6. It will be understood 30 that the hooks 62 are not normally in engagement with the ends 63 and the car is supported by the pivot. By this means, the car will be supported by the hooks in the event of damage to the pivot posts 33.

Referring now to Figs. 3, 4, and 5, my invention contemplates the provision of switch means 70 by which 35 the travel of a car can be diverted from the straight track 11 onto a branch track 71, which includes spaced rails 72 of the same form as the rails 12 described previously. The switch means 70 includes an auxiliary track section 73 which is composed of a pair of auxiliary 40 channel shaped switch rail sections 74, these rails being connected to a yoke member 74' at 75, the member being pivoted at 76 centrally of the main rails. The track section 73 is supported from curved guide members 80 extending between beams 78 and 79 which, in 45 turn, extend between a pair of the towers 20, slide elements 73' on the track section engaging the members 80. Suitable straps 80' extend upwardly from track section 73 and embrace curved guide members 80 for guiding and supporting the track section 73 in its movement from one position to the other. A curved guide plate 81 projecting from branch track 71 serves to additionally support the switch section when the switch section bridges the main line to the branch line while a similar plate 81' may support the switch section when bridging the main line track and the continuation track. It will be evident 50 that sufficient play is provided between the wheels and the upstanding flanges of the channel rails 12 to permit slight variations in the spacing between the rails, especially at the switching position.

The switch track 73 carries a curved gear rack 82 which is arranged substantially concentric to the switch pivots 75. A reversible electric motor 83 is mounted on a stationary framework 84 and has a driving gear 85 which meshes with the gear track 82. By this means, when the motor 83 is energized and its gear 85 is thus rotated, the switch track 73 is pivoted to align its free end with either the main track 11 or the branch track 71, depending upon the direction of rotation of the driving gear. The electric motor 83 may be connected in a circuit which includes a suitable switch (not shown), which may be tripped by the car or by the operator thereof as the car approaches the switch.

Associated with the switch means 70 is a pair of stop gates 90 and 91 adapted for vertical movement above the respective tracks 11 and 71. The gates 90 and 91

are suspended from respective cables 92 and 93 which extend over pulleys 94, the cables being wound onto a drum 95 fast on the armature shaft of the motor 83. Since the gates are located at opposite sides of the axis of the drum 95, when the drum is rotated, one cable is wound further onto the drum to raise the gate carried by the cable and the other cable is unwound from the drum to lower the gate to which this cable is connected. By this arrangement, lowering of either gate effects simultaneous raising of the other gate, this operation being clearly shown in Fig. 5. The gates 90 and 91 are heavily proportioned and, when they are in lower position and engage with their respective tracks, they serve as stops or abutments against which the wheels of the car may engage to prevent the car from passing into the open switch.

As a further precaution against travel of the car into the open switch, red and green warning or signal lights 100 and 101 are employed, see Fig. 5, there being a set of red and green lights adjacent each gate 90 and 91. Electric switches 102 and 103 are connected in the electrical circuits for each set of lights. Each electrical switch 102 and 103 includes a stationary, arcuate contact element having contact portions 104 and 105 separated by a dielectric portion 106. A switch arm 107, pivoted to the framework adjacent the switch means 70, is electrically connected to one side of the circuit and pivotally connected to a gate 90 or 91 at 108. Each contact portion 104, when engaged by the switch arm 107, activates a red light 100 and each contact portion 105 effects lighting of a green lamp 101, the contacts of the respective switches 102 and 103 being reversely disposed so that the green and red lights at opposite sides of the switch means 70 are alternately lighted, in synchronism with the raising and lowering of the gates 90 and 91.

It will be observed from the foregoing description that my invention provides a suspended rapid transit system which is relatively simple in construction, yet highly practical, efficient, and economical in use. As a particular feature of the invention, the transportation car is suspended by means of longitudinally spaced pairs of traction wheels which travel within rails, the latter having upstanding flanges which retain the wheels on the track. By the dual wheel construction, as distinguished from the monorail system, greater stability is attained and side sway is minimized. Due to the resilient mounting of the car, quiet, smooth operation is produced, and this provides greater comfort for the passengers. Moreover, the car is provided with devices for effecting safety so that maximum protection is afforded.

The transit system disclosed herein embodies switch means by which the car can be made to travel along a main track or switched onto a branch track, the mechanism for actuating the switch being simple, yet highly efficient, and adapted for fully automatic operation by conventional controls, not herein disclosed. As an added precaution, the switch embodies stop means and signal lights which together function to avoid running a car through the open switch, the stop means and lights being synchronized and adapted for activation by remote control.

Referring now to Fig. 10, my invention further contemplates a transit system having a monorail 120 which is provided with a horizontal track portion 121 and upstanding flanges 122 at its longitudinal sides. L-shaped supporting members 124 resiliently support the car 10 through the medium of the pivot posts 33 and springs 138. Each supporting member 124 carries at least one wheel 125 which is adapted to roll along the monorail 120. To prevent side sway of the car 10, each supporting member 124 may have a slot 126 for receiving a guide or runner 127 carried by the monorail.

While my rapid transit system has been herein disclosed as embodied in a preferred form of construction, it will be obvious to one skilled in the art that various modification might be made in the structure without departing from the spirit of the invention. Consequently, I do not wish to be limited in this respect, but desire to be afforded the full scope of the appended claims.

I claim as my invention:

1. A suspended railway comprising a pair of substantially parallel channel shaped tracks arranged with their channels opening upwardly, means extending between the channels and upwardly therefrom for supporting said tracks in elevated position, a railway car, an upstanding U-shaped yoke pivoted to the top of the car, a wheel on 15 the inner side of each leg of said yoke having a pneumatic tire and mounted for rotation so the tread of each tire runs in the corresponding channel, and power means for driving the wheels, a bar cross member substantially parallel to the bight portion of the U-shaped yoke and 20 positioned therebelow and supported therefrom and each end projecting laterally outwardly from the pivot, a hook member secured to each side of the car laterally of the pivot with the hooks thereof overlying the ends of said bar cross member and normally having the free extremity thereof adjacent to and spaced a small distance from 25 said bar cross member whereby the car is normally supported by said pivot but in the event of failure of the pivot the car will be supported by the hooks.
2. A suspended railway comprising a pair of substantially parallel channel shaped tracks arranged with their channels opening upwardly, means extending between the channels and upwardly therefrom for supporting said tracks in elevated position, a railway car, an upstanding U-shaped yoke pivoted to the top of the car, a wheel on 30 the inner side of each leg of said yoke mounted for rotation so the tread of each wheel runs in the corresponding channel, and power means for driving the wheels, a bar cross member substantially parallel to the bight portion of the U-shaped yoke and therebelow and supported 35 therefrom and each end projecting laterally outwardly from the pivot, hook members secured to each side of the car laterally of the pivot with the hooks thereof overlying the ends of said bar cross member and normally having the free extremity thereof adjacent to and spaced 40 a small amount from said bar cross member.
